UNITED STATES PATENT OFFICE

157,395

FOOD GRINDER

Daniel L. Marcantonio, Westport, Conn.

Application October 22, 1948, Serial No. 149,239

Term of patent 14 years

(Cl. D89—1)

To all whom it may concern:

Be it known, that I, Daniel L. Marcantonio, a citizen of the United States, residing at Westport, county of Fairfield, State of Connecticut, have invented a new, and useful original, and ornamental Design for a Food Grinder, of which the following is a specification, reference being had to the accompanying drawing, forming part thereof.

Fig. 1 is a top plan view of a food grinder, showing my new design, and

Fig. 2 is a side view thereof.

I claim:

The ornamental design for a food grinder, substantially as shown.

DANIEL L. MARCANTONIO.
